PLATE STACKING AND UNSTACKING MACHINE

John N. Berger, Pittsburgh, Pa.

Application January 21, 1948; Serial No. 3,609

1 Claim. (Cl. 214—8.5)

1 My invention relates to apparatus for assembling articles one-by-one to form a pile or stack and which, with slight modifications, can be also employed for removing the articles from a stack, one-by-one, and has for one of its objects the provision of apparatus that is readily adaptable or adjustable to articles of various diameters.

Another object of my invention is to provide a device of the character referred to that will operate with a minimum of danger of damage to the articles being handled.

Still another object of my invention is to provide article-handling apparatus that can be utilized to stack or unstack articles of widely different character such as metal sheets, slabs, etc., ceramic ware of pottery or glass, plastics of a non-ceramic character, and also including kitchen ware, table ware, trays and articles of similar shapes.

Figure 1 is a plan view of the machine as adapted for use in depiling; or separating one-by-one each article from a stack of articles; Fig. 2 is a side view thereof; Fig. 3 is a view taken on the line III—III of Fig. 1; Fig. 4 is a view taken on the line IV—IV of Fig. 1; Fig. 5 is a plan view on an enlarged scale of a portion of the structure of Fig. 1; Fig. 6 is a view taken on the line VI—VI of Fig. 5; Fig. 7 is a plan view of the machine adapted for use in assembling the articles in stacks or piles; Fig. 8 is a view taken on the line VIII—VIII of Fig. 7, and Fig. 9 shows the dishes of Figs. 6 and 8 in inverted arrangement instead of right side up.

Except for the form and arrangement of some of the article-engaging fingers, the structure of Figs. 1 to 5 is similar to the piling apparatus of Figs. 7 and 8.

Referring first to Figs. 1 to 6, the structure comprises a pedestal or base 10 anchored to a suitable foundation 11. The table 12 is supported on the base 10 through the medium of an adjusting nut 13 that has threaded engagement with a leg or stem 14 of the table and is rotatable to raise and lower such stem and the table to adjust the height of the article-handling members that are carried by the table.

The table has an extension 15 supported therefrom by a cantilever member 16. As shown more clearly in Fig. 3, base plates 17 and 18 are slidably supported on the table and its extension 15 respectively, for adjustment toward and from each other. The members 12 and 15 respectively have bearings 19 and 20 that support a shaft 21 which is driven by a motor 22. The base plates 17 and 18 carry bearings 23 and 24 respectively,

these bearings are movable with the members 17 and 18 and support beveled gear wheels 25 and 26 respectively, that have splined connection with the shaft 21.

5 The members 17 and 18 have tubular extensions 27 and 28 respectively, with which an adjusting screw 29 has threaded engagement. The screw 29 is rotatable on the shaft 21 but is held against turning movement except when making adjustments of the bases 17 and 18. A worm gear 31 is rigidly secured to the screw 29 and is driven by a worm 32 to rotate the threaded sleeve 29 on the shaft 21, to thereby bring the nut-like extensions 27 and 28 toward one another or to move them apart, depending upon the sizes of articles that are to be handled by the apparatus. The worm 32 is driven by a motor 33 through reduction gearing 34. The worm gear shaft carries a pinion 35 that meshes with a gear wheel 36. The gear wheel 36 operates a relay mechanism within the boxes 37 and 38 so that when a pointer 39 on the face of the box 38 is set at a certain point of adjustment for a particular spacing of the article-engaging members, the circuit through the motor 33 will be automatically broken. This automatic control does not comprise part of the present invention; and it will be obvious that the adjustment of the screw 29 could be made manually.

15 The pinion 26 has driving connection with a pinion on an eccentric shaft 41 on which is carried a pair of eccentric elements as shown at 42, the said elements being offset from one another in direction circumferentially of the shaft, as indicated in Figs. 2 and 5. These eccentric elements turn in and operate eccentric hoops 43 and 44. The shaft 41 is supported in bearings 45 and 46 that are mounted on the slide 18.

20 The hoops or yokes 43 and 44 are pivotally connected to slide bars 48 and 49 respectively, that are longitudinally-slidable in a guide block 50 which is secured to the base plate 18. A cover plate 51 is provided to cover the slots in the upper edge of the guide block. The bar 48 has an arm 52 on its outer end that carries fingers 53, while the bar 49 has an arm that carries fingers 54 on its outer end. During rotation of the shaft 41, the fingers 53 will be reciprocated longitudinally and also the fingers 54, in relatively-stepped relation.

25 The beveled gear wheel 25 has driving connection with a pair of eccentric yokes or hoops 56 and 57 that respectively operate fingers 58 and 59 in synchronism with the operation of the fingers 53 and 54, the eccentrics for the fingers 58 and

3

59 operating in the manner shown in Fig. 6 in connection with the eccentrics for the fingers 53 and 54.

Rack fingers or rods 60-61 are carried by the plate 51 and a similar plate 62, respectively, to hold a stack of dishes or other articles against horizontal displacement while they are being operated upon by the various fingers. As shown in Figs. 1 to 6, a stack of articles will be placed in the rack formed by the rods 60-61, and the articles 63 will then be deposited one-by-one upon a conveyor 64 or other suitable support.

In placing the apparatus in operation, the threaded sleeve will be rotated by the worm 32 or in other suitable manner, to adjust the nuts 15 27-28 and hence the slides 17-18 toward or from one another, in accordance with the diameters or widths of the articles to be separated or depiled. This adjustment shifts the bearings 20 23 and 24, together with their associated gear wheels 25 and 26, longitudinally of the shaft 21 and at the same time will correspondingly shift the eccentric mechanism so that the rack fingers 60-61 and the fingers 53-54 and 58-59 will be brought into proper relationship to the articles. 25

Thereupon, the motor 22 will be set in operation to rotate the shaft 24 and the eccentrics. The fingers 54 and 59 will support the stack until the fingers 53-58 have been moved toward one another in position to engage an article that is immediately above the one with which the fingers 54-59 are engaged. Continued operation of the eccentrics will then withdraw the fingers 54-59, allowing the lowermost dish to drop to the conveyor 64. Immediately thereafter, the mechanism will move the fingers 54-59 into position to support the next lowermost dish and the fingers 53-58 withdrawn to allow the stack dishes to be moved down into engagement with the fingers 54-59. Thereafter, the fingers 53 and 58 will be moved into position above the lowermost dish, and the operations continued until all of the dishes or other articles have been discharged or depiled.

In Figs. 7, 8, and 9, I show mechanism constructed and operated in somewhat the same manner as the apparatus of Figs. 1 to 5. In this case however, the article-engaging fingers are operated in a somewhat different manner, in order to pile the dishes or assemble them in a stack. In this arrangement, fingers 66 are operated by an eccentric 67 in the same manner as are the fingers 53-58, at each side of the stack of articles. Lifting fingers 68 are provided at each side of the apparatus, for lifting articles 69 from a conveyor 70, one-by-one, to form a pile as in Fig. 8.

These fingers 68 instead of being reciprocated horizontally as are the fingers 54, are oscillated through an arc by eccentric yokes or hoops 72 that are moved eccentrically as are the hoops 43. The hoops have arms 73 rigidly secured thereto, these arms carrying the fingers 68. The hoops are floatingly connected to the base plate 18a by links 75 so that during rotation of the shaft 41a and arms 73, the fingers 68 will be moved in arcuate paths downwardly and back-

wardly with respect to the articles and then advanced toward the articles and upwardly to lift the articles from the conveyor 70. During this cycle of movement by the arms 73, the fingers 66 will be maintained in position to support the stack of articles. As soon as the fingers 68 have moved an article upwardly against the lower end of the stack, the fingers 66 will be retracted and then projected to bring them into position to support the article last raised by the fingers 68.

It will be seen that, for the most part, the same mechanism can be used to either pile or unpile articles, the principal change required being simply in the substituting of eccentric elements 12 for the eccentrics 43. The various piling and depiling fingers can be made of any suitable material, such as glass-covered steel pins or chrome-plated metal, so as not to mar or discolor fine ware, and so that the fingers themselves will have longer life than would ordinary steel for example. As shown in Fig. 9, dishes or the like can be piled and depiled when they are in inverted positions.

I claim as my invention:

Article-handling apparatus comprising a pair of base members that are supported on slide-ways for adjustment toward and from each other, in a horizontal plane, an eccentric shaft journaled on each base member and each provided with a pair of eccentrics that are relatively offset about the axis of the shaft, yokes on the eccentrics, horizontally-extending fingers pivotally connected to the yokes, guide means for the fingers, and retaining members extending upwardly from the base members, in positions to hold the articles of a stack in relative vertical alinement, the fingers connected to an eccentric yoke of one shaft and the fingers that are connected to the correspondingly mounted eccentric yoke of the other shaft being in a higher plane than the fingers that are connected to the other eccentric yokes, and the fingers that are at each side of the center line of a stack of articles being moved toward and from one another by their eccentrics, to thereby periodically afford vertical support to a stack of articles, by the upper and lower fingers, respectively.

JOHN N. BERGER.
